UNITED STATES PATENT OFFICE.

FRANK G. MIDDLEKAUFF, OF FORRESTON, ILLINOIS.

SHEAF-CARRIER.

SPECIFICATION forming part of Letters Patent No. 357,619, dated February 15, 1887.

Application filed September 10, 1886. Serial No. 213,246. (No model.)

To all whom it may concern:

Be it known that I, FRANK G. MIDDLEKAUFF, a citizen of the United States, residing at Forreston, in the county of Ogle and State of Illinois, have invented certain new and useful Improvements in Sheaf-Carriers, which are fully set forth in the following specification, reference being had to the accompanying drawings, forming a part thereof, 10 wherein—

Figure 1 is a perspective of a portion of a harvester-frame having my improved sheaf-carrier attached thereto, the point of view being from the rear outer corner. Fig. 2 is a 15 side elevation of my sheaf-carrier, shown in full lines in the position of dumping, and in dotted lines in the position to receive the sheaves. Figs. 3 and 4 are side elevations, on a reduced scale, showing slightly modified forms of my device for dumping the carrier. 20

A' and A'' are, respectively, the front and rear bars of the harvester-frame.

B is the sheaf-carrier.

C' is a cranked rock-shaft journaled on the 25 rear bar, A' , having the crank-arm C^{10} and the crank-wrist C^{11} extending stubbleward at right angles to the direction of travel.

C^2 is a similarly-cranked rock-shaft journaled on the front bar, having a similar crank-arm, C^{20} , and the crank-wrist C^{21} parallel with the crank-wrist C^{11} . Upon the two crank-wrists C^{21} and C^{11} the sheaf-carrier B is supported, the wrists being journaled on the lower side thereof. The rock-shaft C' is further provided, at its inner end, with the crank-arm C^{12} , and to the same there is connected the link E , which extends upward in any direction necessary to bring it in convenient reach of the operator. The crank-wrists C^{11} and C^{21} are 35 journaled on the carrier nearer together than their respective shafts C' and C^2 are journaled on the harvester-frame, so that the crank-arms C^{10} and C^{20} converge from the shafts to the wrists. 40

45 The operation of this device is as follows: When the sheaf-carrier is in the position shown in Fig. 1, and in dotted lines in Fig. 2, it is substantially horizontal and at the proper elevation to receive the sheaves from the binder-table F . When it has been sufficiently loaded, 50 the operator will rock the shaft C' by pulling the link E , thereby throwing the crank-arm

C^{10} downward toward a horizontal position, thus carrying the rear end of the sheaf-carrier, which is supported on the crank-wrist C^{11} , 55 downward to the position shown in full lines in Fig. 2. In causing this motion of the rear end, the carrier is carried longitudinally forward, causing the crank-arm C^{20} , upon whose wrist C^{21} the forward end of the carrier is journaled, to move forward from the first position, 60 marked 1, (shown in dotted lines in Fig. 2,) to the second position, marked 2 in dotted lines, and as the crank-arm C^{10} rocks still farther over to the horizontal position the forward 65 end of the carrier returns rearward until the crank-arm C^{20} is substantially vertical, as shown in full lines in Fig. 2, when the crank-arm C^{10} becomes horizontal. Thus, while the rear end of the carrier, controlled by the crank-arm C^{10} , 70 is moved continuously downward and forward, the rear end, supported and controlled in its motion by the crank-arm C^{20} , without materially changing its elevation, has moved first forward and then rearward, so that the carrier, 75 by means of the co-operation of the two cranked supports, is caused to assume an inclined position, and thereby to discharge its contents.

It will be obvious that the crank-arms might be bent downward, instead of upward, from the 80 shafts, respectively, if the bars upon which said shafts are journaled were high enough to make it desirable to so locate the carrier, as shown in Fig. 3. In that case the tilting of the carrier would be effected by raising one 85 end by rocking the shaft, as described, and the shaft so rocked, in order that the carrier should be dumped, would be the forward instead of the rear shaft.

It will also be obvious that to sustain the 90 end whose elevation is substantially unchanged in tilting, any fixed support over which the carrier might reciprocate could be substituted for the rocking support afforded by the crank-shaft C^2 . Such substitution is illustrated in 95 Fig. 4, where the rod C^3 is rigid with the harvester-frame and, protruding stubbleward, supports one end of the sheaf-carrier, which is allowed to rock and slide over it, as compelled by the movement of the actuating crank-shaft 100 C^{10} .

I claim—

1. In combination with the harvester-frame and the sheaf-carrier, a support for one end of

the carrier, pivoted thereto and to the harvester-frame, said pivots being horizontal and at right angles to the direction of travel, and a pivotal support for the other end of the carrier, upon which the same may rock and move longitudinally as the carrier is rocked upon the other support, substantially as set forth.

2. In combination with the harvester-frame, a horizontal rock-shaft journaled thereon at right angles to the direction of travel, and having a crank-arm, a sheaf-carrier journaled at one end on the crank-wrist, and a support for the other end of the carrier, upon which said carrier rocks and moves longitudinally, and means, substantially as described, for rocking the rock-shaft to carry its crank-arm toward a horizontal position, substantially as set forth.

3. In combination with the harvester-frame and the sheaf-carrier, supports for the two ends of the carrier, pivoted thereto and to the harvester-frame, the pivots of said supports

on the frame being farther apart than their pivots on the carrier, substantially as set forth.

4. In combination with the harvester-frame, two horizontal rock-shafts journaled thereon at right angles to the direction of travel and provided with crank-arms, and the sheaf-carrier journaled on the wrists of said crank-arms, the journal-bearings of the shafts on the harvester-frame being farther apart than the bearings of the wrists on the carrier, and means, substantially as set forth, for making one of the shafts to carry its crank-arms toward a horizontal position.

Signed in the presence of two witnesses, at 35
Forreston, Illinois, this 6th day of September,
A. D. 1886.

FRANK G. MIDDLEKAUFF.
